UNITED STATES PATENT OFFICE.

OSCAR F. EKLUND, OF WORCESTER, MASSACHUSETTS.

BELT SHIPPER.

Application filed February 11, 1921. Serial No. 444,212.

To all whom it may concern:

Be it known that I, OSCAR F. EKLUND, a citizen of the United States, residing at Worcester, in the county of Worcester and State of Massachusetts, have invented a new and useful Belt Shipper, of which the following is a specification.

This invention relates to a belt shipper particularly designed for use with cone pulleys. The invention more specifically relates to that type of belt shipper in which two shipping devices co-operate, one for each cone pulley. These devices may be mechanically separate but are designed for simultaneous manual operation to produce a single desired result.

It is one object of my invention to provide a construction by which my improved belt shipper may be conveniently installed under widely varying conditions and, accordingly, important features of my invention relate to improved supporting and attaching devices for a belt shipper.

Another object of my invention is to provide a belt shipper so designed that the belt may be more easily guided on and off of the different steps of cone pulleys.

My invention further relates to improved supporting members for the belt guides and to certain other arrangements and combinations of parts which will be hereinafter described and more particularly pointed out in the appended claims.

A preferred form of my invention is shown in the drawings in which—

Fig. 1 is a front elevation of my improved belt shipper applied to the head stock of a lathe;

Fig. 2 is a plan view of the upper belt guide;

Fig. 3 is a front elevation of the guide shown in Fig. 2;

Fig. 4 is a side elevation of a portion of one of the supports for the upper guide bar;

Fig. 5 is a plan view of a portion of the lower belt guiding device which is attached to the machine head;

Fig. 6 is a similar view showing the position of the belt during the belt shipping operation;

Fig. 7 is an enlarged front elevation, partly in section, of the devices for supporting the lower guide bar on a machine frame;

Fig. 8 is a detail side elevation looking in the direction of the arrow 8 in Fig. 7 but

with certain of the parts in a different position; and

Fig. 9 is a sectional side elevation taken along the line 9—9 in Fig. 5.

Referring to the drawings, I have shown my improved belt shipper in position for moving a belt 10 which connects a driving cone pulley 11 with a driven cone pulley 12 in the head stock of a lathe or other similar machine.

I will first describe the upper portion of my belt shipping mechanism which is used to guide the belt to the different steps of the driving cone pulley 11. This portion of my belt shipping mechanism comprises a belt guide 13 (Fig. 2) mounted on a supporting member or carriage 14 which is slidable along a guide bar 15. The guide bar 15 is preferably of rectangular cross-section and is secured at each end in supporting arms 16 (Fig. 4). The arms 16 have vertical openings therein through which extend rods 17, the upper ends of which are secured in brackets 18.

The brackets 18 are preferably offset as shown in Fig. 1 and may each be secured to the ceiling or other supporting structure by a bolt 19. By swinging the bracket around its bolt 19 a considerable range of adjustment may be secured. It is thus often possible to secure the brackets in place by bolts already provided for other purposes. The rods 17 are vertically adjustable in the brackets 18 and also in the arms 16 so that the elevation of the guide bar 15 may be adjusted as desired.

Rollers 20 are provided in the arms 16 to support and guide a rope 21 secured to a depending projection 22 on the carriage 14. The carriage is thus conveniently moved along the bar 15 by grasping one or the other of the handles 23 at the ends of the rope 21.

The carriage 14 is commonly formed as a single casting having an opening 24 loosely receiving the supporting guide bar 15. Grooved guide rolls 25 are provided in oppositely disposed pairs on the carriage 14 and engage opposite angles of the bar 15 as clearly shown in Fig. 9. The carriage is thus supported in a definite angular position and is freely movable upon the rolls 25, the opening 24 being large enough to clear the bar 15 as the carriage is moved on its rolls.

The lower belt guide and carriage which

are attached to the machine head are substantially the same as that already described, with the exception that a handle 26 (Fig. 5) is secured directly to the carriage and that the belt guide 27 is of slightly different construction and is secured to an upwardly extending projection 28 on the carriage.

In Figs 7 and 8 I have shown attaching devices by which the lower guide bar may be conveniently secured to different types of machines. For this purpose a head 30 (Fig. 7) is provided for each end of the lower guide bar 31, said head having a recess fitting the end of the guide bar and having also a conical bearing surface 32 fitting the conical recess 33 in one end of a member 34 forming part of an extensible link. A bolt 35 is threaded in the end of the bar 31 and secures the parts 30 and 34 firmly to the bar. The second member of the extensible link comprises a pipe or tube 36 having a head 37 threaded or otherwise secured in one end thereof. The opposite end of the pipe 36 is threaded to receive the threaded end of the member 34 and a lock nut 38 is provided for securing the parts firmly in adjusted position.

A short link 40 is provided with two bearing faces perpendicular to each other, one end of the link being pivotally secured to the head 37 and the other end being pivotally secured to a member 41 having a threaded portion intended to fit a threaded hole tapped in a convenient portion of the machine frame. The parts 37, 40 and 41 thus serve the purpose of a universal joint.

With this combination of universal joints and swivel connections I am able to conveniently support the guide bar 31 upon a wide variety of machine frames.

The guide bars 15 and 31 are preferably disposed substantially parallel in horizontal plan to the conical surface of the pulleys 11 and 12, and the belt guides 13 and 27 are given a peculiar angular formation which will now be described. One of these guides in relation to a cone pulley is best shown in Figs. 5 and 6 in which it will be seen that the front and rear faces of the guide are substantially parallel to the supporting guide bar while the side faces of the guide are slightly inclined toward the smaller end of the associated cone pulley. This slight inclination of the sides of the belt guide tends to move the rear edge of the belt outward as it is moved toward the small end of the pulley, as clearly shown in Fig. 6, such outward movement producing an opposite or inward movement of the leading edge of the belt and facilitating the shipping of the belt to a smaller step on the cone. When the movement is reversed,

the following side of the guide forces the rear edge inward and the leading edge is correspondingly turned outward, thus more readily permitting movement to the next larger step of the cone.

Having thus described by invention, the uses and advantages thereof will be readily apparent and it will be clear that changes and modifications may be made therein by those skilled in the art within the spirit and scope of my invention as set forth in the claims. Accordingly, I do not wish to be otherwise limited to the details herein disclosed but what I claim is:—

1. A belt shipper having in combination a single guide bar of angular cross-section, a belt guiding member entirely supported and slideable on said single bar, and grooved rolls disposed in pairs on said member and engaging opposite angles of said bar to support and angularly position said member.

2. A belt shipper for cone pulleys comprising a guide bar supported substantially parallel to the conical surface of each pulley, belt guides slidably supported on said bars, and means to move said guides, each guide having front and rear faces substantially parallel to its supporting bar and having side faces slightly inclined toward the small end of the corresponding pulley as said faces extend toward the axis of said pulley.

3. A belt shipper for cone pulleys comprising a supporting bar mounted in fixed relation to a cone pulley, and a belt guide slidably supported on said bar, the side faces of said guide being slightly inclined toward the small end of the associated cone pulley as said faces extend toward the axis of said pulley.

4. In a belt shipper, a guide bar of rectangular cross-section, heads fitting the ends of said bar and each having a conical bearing surface, supporting devices each having a corresponding conical bearing surface, and means to secure said bar, heads, and supporting devices together in desired angular relation.

5. In a belt shipper, a guide bar and means to support each end of said bar on a machine frame, said means comprising an extensible link, a swivel connection between one end of said link and said bar, a short link pivoted at one end to said extensible link, and an attaching device pivoted to the other end of said short link, the axes of the connections at the two ends of said short link being perpendicular to each other.

In testimony whereof I have hereunto affixed my signature.

OSCAR F. EKLUND.
